INVESTOR:

U. D. Mihill

UNITED STATES PATENT OFFICE.

N. D. MIHILLS, OF HARTFORD, WISCONSIN.

HEATING APPARATUS.

Specification of Letters Patent No. 22,740, dated January 25, 1859.

To all whom it may concern:

Be it known that I, N. D. MIHILLS, of Hartford, in the county of Washington and State of Wisconsin, have invented a new and useful Heat-Controlling Cylinder; and I do hereby declare that the following is a full and exact description thereof, reference being had to the accompanying drawings and to the marks and letters thereon.

10 To enable others skilled in the art to make and use my invention, I will proceed to describe its construction and operation.

Of the drawings forming part of this specification, Figure 1 is an isometrical view 15 of the cylinder, with a part of its exterior or shell removed, showing the arrangement of means within the cylinder; Fig. 2 is a transverse sectional view; Fig. 3, a top or end view; and Fig. 4, a full length side view.

20 Like letters and marks indicate like parts in all the figures of the drawings.

The object of my invention is to prevent the free or rapid passing onward of the products of combustion from the fire-box 25 into the chimney or escape flue, and thus to economize the consumption of fuel.

It is well known that in heating buildings and apartments by stoves and like means, a large part of the heat generated is lost by 30 having too direct and rapid passage through the pipes and flues. Various plans have been suggested and tried for the correcting of this evil, among the more common of which are certain arrangements of pipes and 35 joints, and plates and chambers, looking to the extending of the metal surface exposed to the products of combustion. These arrangements are expensive and occupy very considerable space. It is, therefore, very desirous 40 to have some means which shall be effective, of moderate cost and which will be compact. My cylinder, it is believed, possesses all these qualities; and while it is specially designed to be used with stoves, as 45 will readily be perceived it may be applied to any other means designed for conducting and diffusing heat.

I attach a series of disks of metal (R¹, R², R³, R⁴, R⁵.) to a bar (C) by rods (a) which 50 pass through holes in the shoulders or projections (b) on the bar and which allows each disk a hinge motion on the bar. Each disk is centrally suspended on a rod (e) the ends of which fit into holes in bars (F, F). 55 These bars (F, F), as will be seen with the rods (e) constitute a frame for holding the disk and the bar (C) a movable bar for op-

erating the disks. When the disks are thus attached to the bars (F, F, C), they are placed within the cylinder (A) the bars 60 (F, F,) fitting in the grooves of the cylinder, as shown by Fig. 2. The rod (K) is then passed through a recess in a plate attached to the disks (R⁵), as is common in stove dampers, and by the thumb piece of rod (K), 65 through the bar (C), the entire series of disks can be moved. The ends of the cylinder (A) are made conical as at (B) and then cylindrical again as at (O and I) to admit of the cylinder being connected to the stove or 70 other pipe. Portions of the periphery of each disk are removed as shown at (P), or in place of the removal of such semi-cylindrical piece a crescent shaped piece may be removed, and as is shown by Fig. 1 of the 75 drawings thus making an opening or channel alternating from one side of the cylinder to the other. By this arrangement of disks within the cylinder it will be noticed that in case of injury to any one of the disks or the 80 breaking of one, or of any one of the bars or rods, the whole as a structure may be taken out of the cylinder and the broken part being replaced the whole can again be readily returned within the cylinder,—the change being as easily effected as the removal of an ordinary damper. This arrangement of 85 means, it will be perceived, allows of an uninterrupted flow of the gaseous products of combustion through the cylinder when the 90 disks are so turned as to be in a line parallel to the sides of the cylinder, and of more or less interruption due to the position of the disks. When they are at right angles to the 95 sides of the cylinder the track of the products will be in a serpentine line, as is shown by Fig. 4, and the cylinder is then a very efficient heat radiator and diffuser. The passage of the products of combustion and the escape of the heat can, therefore, very 100 fully and readily be controlled.

I claim—

A heat controlling cylinder in which the regulating disks, shaped as described, are connected with a detachable frame, the same 105 being arranged and operated as hereinbefore specified.

This specification signed this 25th day of November 1858.

N. D. MIHILLS.
